UNITED STATES PATENT OFFICE

143,409

DESIGN FOR A SPRINKLER

Milton S. Dunkelberger, Dayton, Ohio, assignor to
The American Display Company, Dayton, Ohio, a corporation of Ohio

Application December 18, 1944, Serial No. 116,971

Term of patent 14 years

(Cl. D91—1)

To all whom it may concern:

Be it known that I, Milton S. Dunkelberger, a citizen of the United States, residing at Dayton, in the county of Montgomery and State of Ohio, have invented a new, original, and ornamental Design for a Sprinkler, of which the following is a specification, reference being had to the accompanying drawings, forming a part thereof.

I claim:

The ornamental design for a sprinkler, as shown.

MILTON S. DUNKELBERGER.
